United States Patent Office

Des. 191,224
Patented Aug. 29, 1961

191,224

DISHWASHER

John A. Fay, Los Angeles, Calif., assignor to Waste King Corporation, Los Angeles, Calif., a corporation of California

Filed Apr. 19, 1960, Ser. No. 60,246

Term of patent 14 years

(Cl. D49—1)

FIG. 1 is a perspective view showing the top, front and left side of a dishwasher embodying my new design;
FIG. 2 is a front elevational view thereof;

FIG. 3 is a side elevational view showing the right side thereof; and

FIG. 4 is a top view thereof.

I claim:

The ornamental design for a dishwasher, or similar article, substantially as shown.
